(57) **CLAIM**

The ornamental design for a battery case, as shown and described.

DESCRIPTION

FIG. 1 is a front elevational view of a battery case showing my new design;

FIG. 2 is a top plan view thereof;

FIG. 3 is a bottom plan view thereof;

FIG. 4 is a first perspective view thereof;

FIG. 5 is a second perspective view thereof;

FIG. 6 is a third perspective view thereof;

FIG. 7 is a fourth perspective view thereof, showing the battery case in an open position; and,

FIG. 8 is a fifth perspective view thereof, showing the battery case in an open position.

The broken lines are for illustrative purposes only and form no part of the claimed design.
